CENTRALIZED TRAFFIC CONTROL SYSTEM

Richard C. Leake, Rochester, N. Y., assignor to
General Railway Signal Company, Rochester,
N. Y.

Application March 27, 1930, Serial No. 439,323

33 Claims.

(Cl. 246—3)

This invention relates to centralized traffic controlling systems for railroads of the synchronous selector type, and more particularly to an impulse absorbing group of relays for such a system.

The impulse absorbing relay group of the present invention is particularly applicable to the system shown in the prior application of R. C. Leake and Robert M. Phinney, Ser. No. 385,740, to which application reference may be had, if desired. Generally speaking, in the system shown in said prior application, a series of impulses is transmitted to each of the various way stations of the dispatching system, each impulse establishing a separate channel circuit, all of said channel circuits including the same line wire, so that by employing three line wires, a stepping wire, a message wire and a common wire, it is possible to set up as many independent message circuits as there are impulses in one cycle of operation of the system. In said prior application, a relay is required for absorbing each of the impulses at a distant way station, from which it readily appears that at the last way station there would be required as many relays as there are impulses in a cycle.

In accordance with the present invention, it is proposed to assemble a relay group in a circuit arrangement so that a large number of impulses may be absorbed through the medium of a comparatively small number of relays. For instance, if the channel circuits desired to be used at a particular way station are closed respectively at the thirty-third and the thirty-fourth impulses, it would be expedient to be able to absorb impulses 1 to 32 inclusive, and allow the thirty-third and the thirty-fourth impulse to pass to the channel completing relays at such way station.

More specifically, it is proposed to employ two series of stepping relays in which the second series is of a higher order than the first series, and in which a relay of the second group is operated for each operation of all the relays of the first group, so that the relays of the first series may be used over as many times as there are relays in the second series. Further, if desired, an additional relay may be employed to permit each of the relays of the second series to carry out their functions twice.

Another object of the present invention resides in the standardization of various groups of relays such as auxiliary relays, impulse absorbing relays and selecting relays, mounting each of these groups of relays in their own cabinet so that any

one of these cabinets can be replaced by a reserve cabinet in case trouble develops in the wiring of certain of the apparatus.

Other objects, purposes and characteristic features of the invention will be pointed out herein-after and will in part be obvious from the accompanying drawing.

In describing the invention in detail, reference will be made to the single accompanying drawing, showing an auxiliary group, an impulse absorbing group and a selecting group of relays, all located at a way station in the particular form of the invention illustrated, interconnected in a manner so that the impulse absorbing group absorbs 32 electrical impulses.

Referring to the drawings the stepping wire 10 is alternately energized by positive and negative impulses following a period of blank, representing a division between two cycles of impulses, these impulses being applied at the dispatcher's office, and the message wire 11 is energized by current of a particular polarity or is deenergized following immediately the period of each impulse depending upon the character of message that is to be transmitted over the message circuit completed by such impulse, all in a manner more fully described in the prior application above referred to.

The auxiliary relay group includes only the usual polar line relay LR and the usual slow dropping relay K, which relay K clears out or synchronizes the system at the end of each cycle. The impulse absorbing relay group includes a series of relays numbered 1, 2, 3, 4, etc., and conveniently called number relays, a series of relays A, B, C, etc., conveniently called letter relays, a shift relay SH and a transfer relay TR, and the selecting relay group includes the usual channel selecting relay 33 and 34, a signal relay SR, a direction relay DR and a number relay 1a.

At the distant way station under consideration there has been shown a main track comprising rails 12 and a side track comprising rails 13, said side track being at times connected to the main track through the medium of a track switch S. 45 These track rails being insulated in the usual way by insulating joints 14, the usual east bound starting signal E and the west bound entering signal W being provided. It is believed that the present system will be most readily understood 50 by considering the operation of the way side equipment shown in the drawing.

Operation.—Let us assume that it is desired to operate the signal relay SR, this relay preferably being a polar relay of the permanent magnet stick 55

type, which remains in the position to which it was last operated, and in order to do so the dispatcher's office equipment applies a positive potential to the message wire 11 immediately after 5 the thirty-third impulse is transmitted over the stepping circuit, and let us observe how 32 of these impulses are absorbed, so to speak, by the impulse absorbing group.

As heretofore mentioned, the first impulse applied to the stepping line 10 is a positive impulse 10 and operates the contacts 15 and 16 of the relay LR to their right hand position; the contact 15 thus closes the following circuit:—beginning at the positive terminal of the battery 20, wires 21 15 and 22, contact 15 assuming its right hand position, wires 23 and 24, winding of the relay K, wires 25, 26 and 27, back to the battery 20.

The circuit just traced will energize the relay K, but before this relay K has started movement 20 from its deenergized position the following circuits for the relays 1 and 1^a are completed:—(1) beginning at the positive side of the battery 20, wires 21 and 22, contact 15, wire 23, contact 28 25 of the relay K in its normal retracted position, wires 29 and 30, lower winding of the relay 1, wires 31 and 32, back contact 52 of the relay 2, wires 55 and 35, back to the negative terminal of the battery 20, and (2) beginning at positive terminal of the battery 20, wires 21 and 22, contact 30 15 of the relay LR, wire 23, back contact 28 of the relay K, wires 29 and 58, winding of the relay 1^a, wire 59, back contact 68 of the channel selecting relay 33, wires 69, 168, 55 and 35, to the negative terminal of battery 20. As soon as the relay 1 35 has assumed its energized position the following stick circuit will be closed to hold this relay 1 energized irrespective of its pick-up circuit:—beginning at the positive terminal of the battery 20, wires 36 and 37, front stick contact 38 of the relay 1, wire 39, upper winding of the relay 1, wires 40 and 32, back contact 52 of the relay 2, wires 55 and 35 back to battery 20. Similarly, the relay 1^a is stuck up through the following stick circuit:—beginning at the positive terminal 40 of the battery 20, wires 36, 51, 94, 169, 169^a and 180, front stick contact 181 of the relay 1^a, upper winding of this relay 1^a, wire 59, back contact 68 of the relay 33, wires 69, 168, 168^a, 70 and 61, contact 41 of relay K, wires 60 and 35, back to the negative terminal of battery 20.

The relay K will by this time have assumed its attracted position and will have shifted its contacts 28, 41 and 42 to their attracted position, 55 but the shifting of these contacts will not complete any particular circuit, because the only circuit completed is the circuit including the lower winding of the number relay 2, and this circuit has no source of energy contained therein.

Movement of the contact 15 of the line relay 60 to its left hand position in response to the second impulse transmitted closes the following circuit for energizing the number relay 2:—beginning at the negative terminal of the battery 20, wires 27 and 43, contact 15 of the relay LR, wire 23, contact 28 of the relay K in its upper position, wire 44, front contact 45 of the relay 1, wire 46, lower winding of the relay 2, wires 47 and 48, back contact 49 of the relay 3, wires 50, 51 and 36 to the positive terminal of the battery 20.

The completion of this circuit effects energization of the number relay 2, the lifting of the contact 52 thereof breaking the stick circuit for the relay 1, so that the relay 1 again assumes its deenergized position, and further the picking up of the contact 52 of the relay 2 closes the following

stick circuit for the relay 2:—beginning at the negative terminal of the battery 20, wires 35 and 55, front stick contact 52 of the relay 2, wire 53, upper winding of the relay 2, wires 54 and 48, back contact 49 of the relay 3, wires 50, 51 and 36, to 5 the positive terminal of the battery 20.

It is thus seen that the first impulse energizes the number relays 1 and 1^a, while the second impulse energizes the number relay 2. In the same manner, the third impulse transmitted over the 10 stepping line 10 effects energization of the number relay 3 through the front contact 56 of the relay 2, and similarly the fourth impulse transmitted effects energization of the relay 4 through the front contact 57 of the relay 3. The fourth impulse is of course one of negative polarity and with the relay 4 once energized it sticks up through the following stick circuit:—beginning at the negative terminal of the battery 20, wires 35 and 60, front contact 41 of the relay K, wires 61 and 20 15 62, front stick contact 64 of the relay 4, wire 65, upper winding of the relay 4, wires 66 and 67, back contact 38 of the relay 1, wires 37 and 36, to the positive terminal of the battery 20.

The next impulse, namely the fifth impulse, 25 which is of positive polarity, operates the line relay LR to the right thereby picking up the relays A and 1 through the following respective circuits:—(1) beginning at the negative terminal of the battery 20, wires 35 and 60, front contact 41 of the relay K, wires 61, 70 and 71, back contact 72 of the pole changing relay P, wires 73, 74, 75, 76 and 77, back contact 78 of the shift relay SH, wire 79, contact 16 of the relay LR, wire 80, front contact 81 of the relay 4, wires 82, 83, 35 84 and 85, bottom winding of the letter relay A, wire 86, back contact 87 of the relay B, wires 88, 89 and 90, back contact 91 of the pole changing relay P, wires 92, 93, 94, 51 and 36, back to the positive side of the battery 20; and (2) beginning 40 at the positive terminal of the battery 20, wires 21 and 22, polar contact 15 of the relay LR, wire 23, front contact 28 of the relay K, wire 44, back contact 45 of the relay 1, wire 95, back contact 56 of the relay 2, wire 96, back contact 57 of the relay 3, wire 97, front contact 98 of the relay 4, wire 99, back contact 100 of the transfer relay TR, wire 101, front contact 42 of the relay K, wires 102 and 30, lower winding of the relay 1, wires 31 and 32, back contact 52 of the relay 2, wires 55 and 35, to the negative terminal of the battery 20.

With these relays 1 and A once up, the relay 1 will stick up in a manner as already described, and the relay A will stick up through the following stick circuit:—beginning at the negative terminal of the battery 20, wires 35 and 60, front contact 41 of the relay K, wires 61, 70 and 71, back contact 72 of relay P, wires 73, 74, 75, 76 and 104, front stick contact 105 of the relay A, wire 106, upper winding of the relay A, wires 107, 108, 89 and 90, back contact 91 of the relay P, wires 92, 93, 94, 51 and 36, back to the battery 20.

Picking up of the relay 1 will of course effect 65 deenergization of the relay 4 by the opening of its back contact 38, and as soon as the relay 4 drops to its deenergized position, bearing in mind that the letter relay A is now energized, the following pick-up circuit for the shift relay SH 70 is completed:—beginning at the positive terminal of the battery 20, wires 21, 119 and 111, back contact 112 of the relay 4, wires 113 and 114, winding of the relay SH, wire 115, front contact 116 of the relay A, wire 117, back contact 118 of 75

the relay B, wires 119, 120, 26 and 27, back to the battery 20.

The sixth, seventh and eighth impulse, will of course successively pick up the relays 2, 3, and 4

- 5 all in a manner as already herein explained hereinbefore. Picking up of the relay 4 on the eighth impulse will close the following stick circuit for the relay SH:—beginning at the positive terminal of the battery 20, wires 21, 110 and 111, front contact 112 of the relay 4, wire 121, stick contact 122 of the relay SH, wires 123 and 114, winding of the relay SH, wire 115, front contact 116 of the relay A, wire 117, back contact 118 of the relay B, wires 119, 120, 26 and 27, back to the battery 20. Also, with the relay 4 picked up, the ninth impulse of the cycle completes the following pick-up circuit for the relay B:—beginning at the positive terminal of the battery 20, wires 36, 51, 94, 93 and 92, back contact 91 of the relay 20 P, wires 90, 89, 108 and 125, contact 78 of relay SH in its raised position, wire 79, contact 16 of line relay LR, wire 80, front contact 81 of the relay 4, wires 82, 83, 84 and 126, front contact 127 of the relay A, wire 128, lower winding of the relay B, wire 129, back contact 130 of the relay C, wires 131, 74 and 73, back contact 72 of the relay P, wires 71, 70 and 61, front contact 41 of the relay K, wires 60 and 35, back to the battery 20. The completion of this circuit will of course 30 pick up the relay B, which relay will then stick up through a stick circuit including its contact 87, readily traced in the drawing.

Picking up of the relay B will not effect deenergization of the relay A, because relay A will remain stuck up through its front stick contact 105. Picking up of the relay B will however, effect deenergization of the relay SH, because its stick circuit is broken at the back contact 118 of the relay B.

- 40 The ninth impulse transmitted over the stepping circuit will of course pick up the relay 1, as will also impulses 10, 11 and 12 pick up the relay 2, 3, and 4 successively. With the relay 4 now energized in response to the twelfth impulse, and 45 with the shift relay SH deenergized the relay C will be energized upon the thirteenth impulse through the following pick-up circuit:—beginning at the negative terminal of the battery 20, wires 35 and 60, front contact 41 of the relay K, wires 61, 70 and 71, back contact 72 of the relay P, wires 73, 74, 75, 76 and 77, back contact 78 of the relay SH, wire 79, contact 16 of the line relay LR, wire 80, front contact 81 of the relay 4, wires 82, 83 and 133, front contact 134 of the relay B, wire 135, lower winding of the relay C, wires 136, 137 and 90, back contact 91 of the relay P, wires 92, 93, 94, 51 and 36 back to the battery 20.

The relay C, as soon as it has been picked up in response to the closure of the circuit just traced, will of course stick up through its stick circuit, readily traced in the drawing, and including its front stick contact 130. The thirteenth impulse will of course also effect energization of the relay 1 and thereby will effect dropping of the relay 4, and as soon as this occurs the shift relay SH will again be energized through the following pick-up circuit:—beginning at the positive terminal of the battery 20, wires 21, 110 and 111, back contact 112 of the relay 4, wires 113 and 114, winding of the relay SH, wire 115, front contact 116 of relay A, wire 117, front contact 118 of relay B, wire 140, front contact 141 of the relay C, wires 142, 120, 26 and 27, back to the battery 20.

75 For obvious reasons the fourteenth, fifteenth

and sixteenth impulse will again pick up relays 2, 3, and 4 in succession. Picking up of the relay 4 will again close the stick circuit for the shift relay SH. Also, picking up of the relay 4 with the relays A, B and C all stuck up will effect closure of the circuit for the lower winding of the pole changer P as soon as the line relay LR is again energized to its right hand position, which occurs on the seventeenth impulse, so that relays 1 and P are simultaneously 10 picked up on the seventeenth impulse, the pole changer relay P being picked up through the following pick-up circuit:—beginning at the positive terminal of the battery 20, wires 36, 51, 94, 93 and 92, back contact 91 of the relay P, wires 15 90, 89, 108 and 125, front contact 78 of the relay SH, wire 79, contact 16 of the line relay LR, wire 80, front contact 81 of the relay 4, wires 82 and 144, front contact 145 of the relay C, wire 146, lower winding of the relay P, wires 147 and 20 73, back contact 72 of the relay P, wires 71, 70 and 61, contact 41 of the relay K, wires 60 and 35, back to the battery 20.

Picking up of the pole changer relay P effects closure of its stick circuit readily traced in the drawing and including the front stick contact 148 of the relay P. Also, picking up of the relay P effects polarity reversal on each of the relays A, B and C, but not on the relay P, and since each of these relays are included in a stick circuit, momentary dropping of relays A, B, C and SH will result and will effect permanent deenergization thereof, in that their stick circuits are broken. The seventeenth, eighteenth, nineteenth and twentieth impulse, will therefore effect respective energization of the relays 1, 2, 3, and 4, all in a manner as already explained. Also, impulses 21, 22, 23 and 24 will effect respective energizations of the relays 1 and A, and the relays 2, 3 and 4.

Further, the reception of impulses 25, 26, 27 and 28 will result in the respective energization of relays 1 and B, and relays 2, 3 and 4. Reception of impulses 29, 30, 31 and 32 will result in the respective energization of relays 1 and C, and relays 2, 3 and 4. It should now be noted that contact 150 of the relay C is closed at a time when the pole changer contacts 72 and 91 of the relay P are in their attracted position. It should further be noted that the shift relay SH is now deenergized, but will again be picked up as soon as the relay 4 again drops, this occurring on the twenty-ninth impulse, which twenty-ninth impulse effects energization of the relay 1 and dropping of the relay 4, so that the transfer relay is energized in response to picking up of the shift relay SH with the relays C and P energized, which occurs at the twenty-ninth impulse transmitted. This energizing circuit for the transfer relay TR may be traced as follows:— 60 beginning at the positive terminal of the battery 20, wires 21, 110 and 151, front contact 152 of the relay SH, wire 153, winding of the transfer relay TR, wire 154, front contact 150 of the relay C, wires 155 and 90, front contact 91 of the pole changer relay P, wires 71, 70 and 61, front contact 41 of the relay K, wires 60 and 35, back to the battery 20.

With the transfer relay TR now energized its front contact 100 connects the wire 99 to the transfer wire 160, but no current will be applied to this transfer wire 160 until the thirty-third impulse, at which impulse the relay 4 is up, the relay 3 is down and the line relay LR is toward the right, at which time energy may flow to the 75

channel selecting relay 33 through the following circuit:—beginning at the positive terminal of the battery 20, wires 21 and 22, contact 15 of the line relay LR toward the right, wire 23, 5 front contact 28 of the slow acting relay K, wire 44, back contact 45 of relay 1, wire 95, back contact 56 of relay 2, wire 96, back contact 57 of relay 3, wire 97, front contact 98 of relay 4, wire 99, front contact 100 of the transfer relay 10 10 TR, wire 160, front contact 161 of the relay 1^a, wire 162, lower winding of the relay 33, wires 163 and 164, back contact 165 of the relay 34, wires 166, 167, 168^a, 70 and 61, front contact 41 of the relay K, wires 60 and 35, back to the negative 15 terminal of the battery 20. The completion of this circuit will of course pick up the relay 33, which relay 33 when picked up will stick up through a stick circuit including its front stick contact 170, thereby resulting in the dropping 20 of the relay 1^a, its circuit being broken at the back contact 68 of the relay 33. As heretofore mentioned, current of a positive polarity will momentarily be applied to the message circuit at a suitable dispatcher's office (not shown), so 25 that the relay SR included between the message wire 11 and the common return wire C and including the front contact 171 of the relay 33 will be operated toward the right, thereby connecting the terminal B of a suitable battery to the 30 pole changer contact 172 of the direction relay DR, through the medium of the polar contact 173 of the signal relay SR. This operation of the signal relay SR from its left hand to its right hand position will apply energy to the eastbound 35 starting signal E through the medium of contacts 173 and 172, providing of course that traffic conditions in advance are safe as determined by the usual home and distant relays of the railway signalling system (not shown).

40 Let us now assume that on the thirty-fourth impulse of a particular operating cycle current of negative polarity is applied to a message wire 11 at the dispatcher's office; this thirty-fourth impulse will of course pick up the relay 34 through 45 the front contact 175 of the channel selecting relay 33, so that the current of negative polarity on the message wire may pass to the direction relay DR, through the back contact 171, of the channel selecting relay 33 and the front contact 176 of 50 the channel selecting relay 34, whereby the direction relay DR is operated to its left hand position causing the east bound signal E to be moved to the stop position and permitting the west bound signal W to be cleared in accordance with traffic 55 conditions ahead (this means not having been shown specifically). As pointed out in said prior application, when the operating cycle has been completed, a period of blank (stepping line deenergized) will elapse, in which period the slow acting relays K at the various wayside locations will 60 assume their deenergized position, thus restoring the system to normal by deenergizing the relays 4, 34, P, SH and TR upon the opening of front contact 41.

65 From the foregoing consideration it is apparent that even though the impulse absorbing relay group only includes 10 relays it has been made possible to absorb 32 electrical impulses thereby, and pass the thirty-third impulse on to the selecting relay group. It also is apparent that the letter relays A, B and C have been used twice, and 70 the number relays 1, 2, 3 and 4 have been used 8 times, so that considerable economy may be obtained in using an impulse absorbing relay group, 75 such as shown in the drawing and as has been

described hereinbefore. It should also be understood that the impulse absorbing group of relays may also be used for channel selecting purposes, for instance, a contact on the transfer relay closed when this relay is up may connect the 5 message wire 11 to channel selecting contacts of the relays 1, 2, 3 and 4, as shown in the aforementioned prior application.

Having thus shown and described one rather specific arrangement of relays whereby a larger 10 number of impulses may be absorbed than relays employed, it is desired to be understood that the particular circuit arrangements shown and described have not been selected for the purpose of showing the exact construction preferably employed in practicing the invention, nor the scope of the present invention, but that the particular circuit arrangement illustrated has been selected for the purpose of showing the underlying principles of the invention, for instance, one principle 15 resides in allowing the impulses to run through the relays 1, 2, 3 and 4, for each of the letter relays A, B or C picked up or stuck up, another principle of which resides in the dropping of the letter relays A, B and C in response to the picking 20 up of a repeat or pole changing relay, so that these letter relays A, B and C may be picked up a second time. In view of these facts it is desired to be understood that the present invention has a broader scope than the particular circuit arrangement illustrated, and that various changes, 25 modifications and additions may be made to adapt the inventions to the particular problem encountered in practicing the same. For instance, if it is desired to absorb only 31 impulses, 30 instead of 32 impulses the transfer wire 160 may be closed only when the relay 3 is energized instead of when the relay 4 is energized, or if it is desired to absorb only 29 impulses the transfer wire 160 would be connected to a front point 40 through a front contact of the relay 1; also, if desired a larger number or less number of number relays and letter relays may be employed, so that any desired number of electrical impulses may be absorbed by slight modifications in the 45 particular circuit arrangement illustrating the impulse absorbing relay group shown, all without departing from the spirit or scope of the present invention, except as demanded by the scope of 50 the following claims.

What I claim is:—

1. An impulse absorbing group of relays for centralized traffic controlling systems for railways for delivering impulses only after a predetermined number of impulses have been received 55 comprising, a series of stepping relays of the first order, a series of stepping relays of a second order, means interconnecting said relays so that all of said relays of the first order will operate successively for each of the relays of the second 60 order operated, and means for always delivering the impulses as they are received only when a predetermined number of impulses have been absorbed.

2. An impulse absorbing group of relays for 65 centralized traffic controlling systems for railways for delivering impulses only after a predetermined number of impulses have been received comprising, a series of stepping relays of the first order, a series of stepping relays of a 70 second order, means interconnecting said relays so that all of said relays of the first order will operate successively for each of the relays of the second order operated, means for always delivering the impulses as they are received only after a 75

- predetermined number of impulses have been absorbed, and means for establishing message circuits by the impulses delivered.
3. An impulse absorbing group of relays for centralized traffic controlling systems for railways for delivering impulses only after a predetermined number of impulses have been received comprising, a series of stepping relays of the first order, a series of stepping relays of a second order, a relay of the third order, means interconnecting said relays so that all of said relays of the first order will operate successively for each of the relays of the second order operated and so that all of said relays of the second order will be permitted to operate successively for the second time in response to operation of said relay of the third order, and means for delivering the impulses as they are received after a predetermined number of impulses have been absorbed.
4. An impulse absorbing group of relays for centralized traffic controlling systems for railways for delivering impulses only after a predetermined number of impulses have been received comprising, a series of stepping relays of the first order, a series of stepping relays of a second order, a relay of the third order, means interconnecting said relays so that all of said relays of the first order will operate successively for each of the relays of the second order operated and so that all of said relays of the second order will operate successively for the second time in response to operation of said relay of the third order, means for delivering the impulses as they are received after a predetermined number of impulses have been absorbed, and means for establishing message circuits by the impulses delivered.
5. An impulse absorbing group of relays for centralized traffic controlling systems for railways for delivering impulses only after a predetermined number of impulses have been received comprising, a series of stepping relays of the first order, a series of relays of a second order, means for picking up and sticking up a relay of the second order for each successive operation of all the relays of the first order and for effecting repeat operation of said relays of the first order in response to impulses received, and means for delivering the impulses as they are received when all of said relays of the second order have been stuck up.
6. An impulse absorbing group of relays for centralized traffic controlling systems for railways for delivering impulses only after a predetermined number of impulses have been received comprising, a series of stepping relays of the first order, a series of stepping relays of a second order, means for picking up and sticking up a relay of the second order for each successive operation of all the relays of the first order and for effecting repeat operation of said relays of the first order in response to impulses received, means for delivering the impulses as they are received when all of said relays of the second order have been stuck-up, and means for establishing message circuits by the impulses delivered.
7. An impulse absorbing group of relays for centralized traffic controlling systems for railways for delivering impulses only after a predetermined number of impulses have been received comprising, a series of stepping relays of the first order, a series of stepping relays of a second order, means for picking up and sticking up a relay of the second order for each successive operation of all the relays of the first order and
- for effecting repeat operation of said relays of the first order in response to impulses received, means for deenergizing said relays of the second order when they have all been stuck up for the first time, so that they may be successively stuck up again, and means for delivering the impulses as they are received when all of said relays of the second order have been stuck up for the second time, and means for establishing message circuits for the impulses delivered.
8. A centralized traffic controlling system for railroads comprising, line relay, a series of neutral relays energized successively as said line relay is operated, a message circuit completed after said series of neutral relays have been operated, and means requiring said series of neutral relays to be successively energized two times during a particular cycle before said message circuit is completed.
9. In a train dispatching system of the selector type, the combination with a plurality of stepping relays successively picked up in accordance with stepping impulses applied to a line circuit connecting two spaced stations, a stick relay picked up when the last one of said stepping relays has been picked up, a stick circuit for said stick relay, and a contact controlled by said stick relay for causing said series of stepping relays to again be picked up successively in accordance with stepping impulses on said line circuit.
10. In a train dispatching system of the selector type, the combination with a plurality of stepping relays successively picked up in accordance with stepping impulses applied to a line circuit connecting two spaced stations, a stick relay picked up when the last one of said stepping relays has been picked up, a stick circuit for said stick relay including a front contact of one of said stepping relays, and a contact controlled by said stick relay for causing said series of stepping relays to again be picked up successively in accordance with stepping impulses on said line circuit.
11. A train dispatching system comprising, a local office and a distant way station, a stepping circuit connecting said office and way station, means at said office to impress on said line circuit a series of stepping impulses followed by a period of deenergization of said line circuit, a series of stepping relays energized successively, one relay being energized for each impulse on said stepping circuit, a stick relay for repeating said series of stepping relays and causing them to be again successively picked up, a slow acting relay actuated during said period of deenergization of said line circuit, and a stick circuit for said stick relay including a contact of said slow acting relay.
12. A train dispatching system comprising, a local office and a distant way station, a stepping circuit connecting said office and way station, means at said office to impress on said line circuit a series of stepping impulses followed by a period of deenergization of said line circuit, a series of stepping relays energized successively, one relay being energized for each impulse on said stepping circuit, a stick relay picked up by one of said stepping relays for repeating said series of stepping relays and causing them to be again successively picked up, a slow acting relay actuated during said period of deenergization of said line circuit, and a stick circuit for said stick relay including a contact of said slow acting relay.
13. A train dispatching system comprising, a local office and a distant way station, a stepping

- circuit connecting said office and way station, means at said office to impress on said line circuit a series of stepping impulses followed by a period of deenergization of said line circuit, a series of stepping relays energized successively one relay being energized for each impulse on said stepping circuit, a stick relay picked up by one of said stepping relays for repeating said series of stepping relays and causing them to be again successively picked up, a slow acting relay actuated during said period of deenergization of said line circuit, a stick circuit for said stick relay including a pole-changing contact, means for operating said pole-change contact to drop said stick relay when it has performed its repeat-initiating function, a second stick relay for performing a repeat-initiating function, and a stick circuit for said second stick relay including a contact actuated by said slow acting relay.
14. A train dispatching system comprising, a local office and a distant way station, a stepping circuit connecting said office and way station, means at said office to impress on said line circuit a series of stepping impulses followed by a period of deenergization of said line circuit, a series of stepping relays energized successively one relay being energized for each impulse on said stepping circuit, a stick relay picked up by one of said stepping relays for repeating said series of stepping relays and causing them to be again successively picked up, a slow acting relay actuated during said period of deenergization of said line circuit, a stick circuit for said stick relay including a pole-changing contact, means for operating said pole-change contact to drop said stick relay when it has performed its repeat-initiating function, a second stick relay for performing a repeat-initiating function, a stick circuit for said second stick relay including a contact actuated by said slow acting relay, and railway traffic controlling apparatus controlled by said stepping relays.
15. In a train dispatching system of the selector type, the combination with a line relay operated intermittently in accordance with impulses transmitted over a line circuit, a series of relays picked up one at a time in accordance with operation of said line relay and each having a stick circuit deriving its energy from the same bus wires, and means for reversing the polarity of said bus wires to effect dropping of all of said stick relays.
16. In a train dispatching system of the selector type, the combination with a line relay operated intermittently in accordance with impulses transmitted over a line circuit, a stick relay picked up in response to a particular step of operation of said line relay, a stick circuit for said stick relay excluding a contact of said line relay but including its own front contact, and means for reversing the polarity of a current source in said stick circuit to effect dropping of said stick relay but leaving available said source for the purpose of holding said stick relay energized in response to a second picking up of said stick relay.
17. In a centralized traffic controlling system, the combination with a stepping circuit connecting a central office and a plurality of way stations; a series of stepping relays, a pick up circuit for each even relay which is closed only if the particular distinctive impulse impressed on the stepping circuit for the step corresponding to that relay is of a particular character, the next preceding stepping relay is attracted, and a relay

which can manifest whether the step is an even or an odd step manifests an even step, and a pick up circuit for each odd relay which can be closed only if the distinctive impulse impressed on the stepping circuit for the step corresponding to that particular relay is of a particular character, the next preceding stepping relay assumes its attracted position, and the relay which can manifest whether the step is an even or an odd step manifests an odd step. 10

18. In combination, a neutral control relay, a bank of neutral stepping relays having pick-up circuits, and means governed by said control relay and including a separate relay for successively energizing the pick-up circuits of said stepping relays only one for each successive energization of said neutral control relay and only during such energization of said neutral control relay. 15

19. In combination, a control contact capable of being opened and closed, a plurality of stepping relays having pick-up circuits, a single half step relay, means actuating said half step relay for each time said control contact is opened, and means including said half step relay for successively energizing said pick-up circuits of said stepping relays only for the successive closures of said control contact. 20

20. In combination, a control contact capable of being opened and closed, a plurality of stepping relays having pick-up circuits, a single half step relay having a contact capable of being actuated to either of two positions, means actuating said contact of said half step relay to an opposite position for each time said control contact is opened, and means including the contact of said half step relay for successively energizing said pick-up circuits of said stepping relays only for the successive closures of said control contact. 30

21. In combination, a neutral control relay, a plurality of neutral stepping relays, a single half step relay having a two position contact, a pick-up circuit for each stepping relay including a front contact of its next preceding relay, means actuating the contact of said half step relay to alternate positions for successive deenergizations of said neutral control relay, and means including said contact of said half step relay and a front contact of said neutral control relay for energizing said pick-up circuits of said stepping relays successively. 45 50

22. In combination, a control relay having contacts operable to either of two positions, a plurality of stepping relays, a half step relay having a half step contact operable to either of two positions, a pick-up circuit for each odd numbered stepping relay including a front contact of said control relay and said half step contact in one of its positions, a pick-up circuit for each even numbered stepping relay including a front contact of said control relay and said half step contact in the other of its positions, and circuit means for said half step relay including a back contact of said control relay and front contacts of said stepping relays, whereby said stepping relays are picked up successively upon successive energizations of said control relay, and whereby said half step relay actuates its half step contact to the opposite position for each successive deenergization of said control relay. 55 60 65 70

23. In combination, a neutral control relay, a bank of neutral stepping relays of the single armature type, a pick-up circuit for each of said stepping relays, and means including a separate relay and said neutral control relay for success- 75

sively energizing the pick-up circuits of said stepping relays only upon, and only one for, each successive energization of said neutral control relay.

- 5 24. In combination; a control relay having a control contact operable to either of two positions; a plurality of stepping relays; a half step relay; means actuating said half step relay for each operation of said control contact to one of its said two positions; and control means governed by said control contact and said half step relay for actuating said stepping relays successively, one for each operation of said control contact to the other of its said two positions, whereby 10 said successive actuations of said stepping relays occur alternately with the actuations of said half step relay.

- 15 25. In combination, a series of stepping relays, a source of current, an impulsing relay when successively operated to one position to sequentially energize said stepping relays, and means, effective when said impulsing relay is successively operated to another position and said stepping relays are successively actuated to their 20 energized positions, to successively select alternate polarities for said energization with said impulsing relay in its said one position.

- 25 26. In combination, an impulse relay operated by current irrespective of polarity, odd numbered counting relays operated by current of one polarity, even numbered counting relays operated by current of another polarity, means including said odd and even counting relays for counting respective odd and even impulses received by said impulse relay, and a relay common to all of said counting relays and controlled jointly by said impulse relay and said counting relays for selecting opposite polarities alternately.

- 30 27. In combination; a neutral control relay; a plurality of neutral stepping relays; a single neutral half step relay; a pick-up circuit for each odd stepping relay including a front contact of its next preceding stepping relay, except in the case of the first stepping relay, a contact of said control relay closed in one position, and a contact of said half step relay closed in one position; a pick-up circuit for each even stepping relay including a front contact of its next preceding stepping relay, a contact of said control relay closed in one position; a stick circuit for each of said stepping relays closed when the corresponding stepping relay is picked up and maintained closed until the last stepping relay has picked up; a pick-up circuit for said half step relay including a contact of said control relay closed in its said other position and contacts of said stepping relays, whereby said half step relay is picked up following the picking up of each odd stepping relay; and a stick circuit for said half step relay including its own front contact and a contact of said control relay in its said one position.

- 35 28. In combination; a neutral control relay; a plurality of neutral stepping relays; a single neutral half step relay; a pick-up circuit for each odd stepping relay including a front contact of its next preceding stepping relay, except in the case of the first stepping relay, a contact of said control relay closed in one position, and a contact of said half step relay closed in one position; a pick-up circuit for each even stepping relay including a front contact of its next preceding stepping relay, a contact of said control relay closed in one position, and said contact of said half step relay closed in its other position; 40 75 a stick circuit for each of said stepping relays

closed when the corresponding stepping relay is picked up and maintained closed until the last stepping relay has picked up; pick-up circuits for said half step relay closed when a contact of said control relay is closed in its said other position 5 and an odd numbered stepping relay is the last operated stepping relay; stick circuits for said half step relay closed when a contact of said control relay is in its said one position and an odd numbered stepping relay is the last operated 10 stepping relay; and electro-responsive means controlled by said stepping relays.

29. In combination; a line circuit having a series of impulses impressed thereon; a line relay for repeating said impulses; a slow acting relay 15 controlled by said line relay so as to be picked up at the beginning of each series of impulses and dropped at the end of each series; a series of stepping relays; a pick up circuit for the first stepping relay of said series controlled by said 20 line relay and including a back contact of said slow acting relay and a back contact of the next succeeding stepping relay; a pick up circuit for each of the remaining stepping relays, except the last, controlled by said line relay and including a 25 front contact of said slow acting relay, a front contact of the next preceding stepping relay and a back contact of the next succeeding stepping relay; a pick up circuit for the last stepping relay of said series controlled by said line relay and 30 including a front contact of said slow acting relay, a front contact of the next preceding stepping relay and a back contact of said first stepping relay of said series; a transfer relay; and an auxiliary pick up circuit for the first stepping 35 relay controlled by said line relay and including a front contact of said slow acting relay, a front contact of said last stepping relay, a contact of said transfer relay and a back contact of the next succeeding stepping relay; whereby said stepping 40 relay bank can operate through a second time in response to said impulses only provided said contact of said transfer relay is closed.

30. A train dispatching system comprising, a local office and a distant way station, a stepping 45 circuit connecting said office and said way station, means at said office for impressing on said line circuit a series of stepping impulses followed by a period of deenergization of said line circuit, a series of stepping relays energized successively one relay for each impulse on said stepping circuit during a first part of said series of impulses, a stick relay picked up when the last stepping relay of said series is picked up for causing said stepping relays to be again successively 55 picked up during a second part of said series of impulses, a slow acting relay picked up at the beginning of said series of impulses and dropped during said period of deenergization of said line circuit, and a stick circuit for said stick relay including a front contact of said slow acting relay.

31. A train dispatching system comprising a stepping circuit connecting a control office and a way-station, means at the control office to impress on said line circuit a series of stepping 65 impulses followed by a period of deenergization of said line circuit, a series of stepping relays energized successively one relay for each impulse on said stepping circuit, a slow acting relay picked up at the beginning of said series of impulses and dropped away during said period of deenergization of said line circuit, a stick circuit for each of said stepping relays closed dependent upon the picked up condition of said slow acting relay, a 70 75

stick relay picked up by the picking up of the last stepping relay of said series, a stick circuit for said stick relay closed dependent upon the picked up condition of said slow acting relay, and 5 pole changing means for reversing the polarity of energy on certain of said stick circuits for said stepping relays whereby all of said stepping relays are dropped away.

32. In combination, a neutral control relay, a 10 bank of neutral stepping relays of the single armature type, a pick up circuit for each of said stepping relays, a separate relay actuated to opposite positions upon alternate operations of said control relay, and circuit means controlled by 15 said control relay and said separate relay for successively energizing the pick up circuits of said stepping relays only one such pick up circuit for

each successive energization of said neutral control relay.

33. In combination, a line circuit having a series of impulses impressed thereon, a stepping relay bank, a first and a second step-by-step means, 5 means responsive to said impulses on said line circuit for causing said first step-by-step means to operate through all of its steps for each step of said second step-by-step means, and means always causing said stepping relay bank to be responsive to said impulses on said line circuit only when said second step-by-step means has operated through all of its steps, whereby a predetermined number of impulses of said series is absorbed before the said stepping relay bank is 10 operated.

RICHARD C. LEAKE.

DISCLAIMER

2,042,670.—*Richard C. Leake*, Rochester, N. Y. CENTRALIZED TRAFFIC CONTROL SYSTEM. Patent dated June 2, 1936. Disclaimer filed October 23, 1937, by the assignee, *General Railway Signal Company*.
Hereby enters this disclaimer to claim 9 of said Letters Patent.
